UNITED STATES PATENT OFFICE.

WARREN B. FLANDERS, OF PHILADELPHIA, PENNSYLVANIA, ASSIGNOR TO WESTINGHOUSE ELECTRIC & MANUFACTURING COMPANY, A CORPORATION OF PENNSYLVANIA.

GOVERNOR.

Application filed November 24, 1920. Serial No. 426,159.

To all whom it may concern:

Be it known that I, WARREN B. FLANDERS, a citizen of the United States, and a resident of Philadelphia, in the county of Philadelphia and State of Pennsylvania, have invented a new and useful Improvement in Governors, of which the following is a specification.

My invention relates to governors, particularly of the fly-ball and spring type, and has for its object to provide apparatus of the character designated which shall be capable of operating at different speeds but with substantially a constant percentage of regulation.

In spring loaded governors, as heretofore constructed, the common practice has been to provide means for varying the compression of the spring in order to adapt the governor for the performance of its governing function at different speeds. The difficulty with a governor of this type is that the percentage of regulation varies, that is, for high speeds the regulation is either too small or the governor becomes isochronous, and for low speeds, the percentage of regulation becomes too great. In order to overcome this difficulty, I have provided an abutment or supporting member for one end of the spring which coacts with the convolutions thereof in such wise that when the spring is adjusted for predetermined speeds the scale thereof is correspondingly changed so as to maintain substantially constant the percentage of regulation. Preferably, I employ a nut with convolutions so arranged that, as the spring is compressed, a greater helical length thereof comes in contact with the nut, thereby decreasing the effective face or helical length of the spring.

Apparatus embodying features of my invention is illustrated in the accompanying drawings, forming a part of this application, in which:

Fig. 1 is a side elevation of a governor, with the parts shown in section, illustrating my invention; and

Figure 2 is a detail view partly in section of the apparatus embodying my improvement.

In the drawing, a governor shaft 10 is operatively connected in any suitable manner with a prime mover whose speed it is desired to control, the upper end of said shaft being threaded to an amount sufficient

to allow the threaded nut 12 a wide range of operation in compressing or releasing the helical spring 13 of uniform pitch. Bearing against the threaded nut 12, is a convoluted abutment or nut member 14, slidably mounted upon the governor shaft 10, and the periphery of this nut member is provided with a helical groove 15 of varying pitch in which traverse the upper coils of the helical spring 13, the base of said spring resting upon the flanged base 16 which is also slidably mounted upon the governor shaft 10. Effective pressure is exerted upon the base 16 by the rollers 17 of arms 18 or other equivalent means, pivoted at 19 to a yoke 20 provided with governor weights 21 which, by their rotation, exert an effective force upon the spring 13, through the arms 18, rollers 17 and base 16. The yoke or support 20 is attached to the shaft 10 in the usual manner. The reciprocating sleeve 22 is connected to the arms 18 by the links 23. Motion is transmitted to the inlet valve 24, or other speed controlling element, by a lever 25, non-rotatingly connected in any suitable manner to the reciprocating sleeve 22.

From the construction above set forth, it will be seen that, as the tension of the spring 13 is increased by adjusting the nut 12, the convolutions of the abutment or nut member 14 engage the convolutions of the spring progressively. In other words, as the tension is increased, an increasing helical length of the spring comes in contact with the nut thereby resulting in a decrease of the effective face or helical length of the spring.

The operation of my governor will be better understood by reference to Fig. 2. As above set forth, the nut 12 is turned on the governor shaft in order to change the longitudinal position of the abutment or support member 14. It will be seen that, as the spring is compressed, a greater length of the convolutions thereof will be in contact with the convolutions of the nut or support member thereby resulting in a change in the scale of the spring.

Fig. 2 shows the governor weights in two extreme positions and in a mean position. Assume that the governor operates at 100 R. P. M., average speed, in the intermediate or mean position, at 102 R. P. M. in the outward position and at 98 R. P. M. in the

inward position. If the spring has 10 free coils at 100 R. P. M., and is under a pressure of 100 pounds, then at 98 R. P. M. the pressure will be 96 pounds and at 102

5 R. P. M. the pressure will be 104 pounds. Hence the spring pressure will change 8 pounds between the positions indicated.

If the spring pressure is increased to 400 pounds at the mean position, the corresponding speed will be 200 R. P. M. Without my 10 novel form of abutment, the pressure at the outer position would be 404 pounds for a speed of 201 R. P. M. and for the inner position the pressure would be 396 pounds for 15 a speed of 199 R. P. M. It is obvious that this is a less speed variation than desired. Accordingly, with my novel form of supporting member for one end of the spring, the number of active coils or the active helical length, may be reduced. With 20 400 pounds pressure, the number of active coils would be reduced to one-fourth of the original number and the scale of the spring would be four times its original value so 25 that the pressure would change 16 pounds, instead of 4 pounds, when the governor weights move between the extreme positions indicated, the speed for the outer position being 204 R. P. M. instead of 201 R. P. M., 30 and, for the inner position, 196 R. P. M., instead of 199 R. P. M., thereby resulting in the same percentage of regulation as in the case assumed above for 100 R. P. M. average speed.

35 It is to be understood that the speeds and pressures mentioned above are used merely for illustrative purposes to render clearer the principle of the invention.

From the above, it will be seen that my invention comprises a simple means for supporting one end of a governor spring in such a manner that when the spring has its tension changed for different speeds the number of free coils, or the active helical length, is automatically varied in order to maintain substantially constant the percentage of regulation for different speeds.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. In a governor, the combination of a spindle, a plurality of weights carried by 60 and mounted to swing about axes which are transverse to the axis of the spindle, inwardly-projecting arms carried by the weights, spring means cooperating with the inward-projecting arms to oppose the centrifugal effect of the weights, and an abut-

ment member for the other end of the spring including a helical rib engaged between convolutions of the spring and decreasing in pitch in the direction away from said arms.

2. In a governor, the combination of a plurality of weights, a spring for opposing the centrifugal effect of said weights, and an abutment member for holding the spring under compression, said abutment member having a helical rib, which engages between convolutions of the spring and which decreases in pitch in the direction away from the weights.

3. In a governor, the combination of a spindle, a supporting member carried by the spindle, weights pivotally connected to the supporting member about axes which are transverse with respect to the axis of the spindle, inwardly-extending arms carried by the weights, a spring surrounding the spindle and cooperating with said arms to oppose the centrifugal effect of the weights, a member cooperating with the end of the spring remote from said arms and having a rib which engages between convolutions of the spring and which is of decreasing pitch in the direction away from said arms, and adjustable means carried by the spindle and cooperating with said member for maintaining the spring under compression.

4. The combination with a governor having centrifugal means to secure actuation of a device in one direction and a spring for securing actuation of the device in the other direction, of supporting means for one end of the spring for holding the latter normally under compression and having a helical rib which is arranged between convolutions of the spring and which decreases in pitch in the direction of the supported end of the spring.

5. In a governor, the combination of centrifugal means, spring means opposing the centrifugal means, and an abutment for the spring means having convolutions of varying pitch fitting between the convolutions of the spring.

6. In a governor, the combination of centrifugal means, a helical spring of uniform pitch opposing the centrifugal means, means for adjusting the tension of the spring, and means for supporting one end of the spring comprising a member with convolutions of varying pitch fitting between the convolutions of the spring whereby the active helical or face length of the latter may be varied as the tension is varied.

7. In a governor, the combination of centrifugal means and an opposing spring with a supporting member having supporting means of varying pitch arranged between the convolutions of the spring adapted to vary the active face or helical length of the spring for different speeds to secure a substantially constant percentage of regulation.

8. In a governor, the combination of a shaft, centrifugal means, and a spring, a supporting member surrounding the shaft for one end of the spring and having convolutions of varying pitch fitting between the convolutions of the spring, and means carried by the shaft and acting on the member to secure different degrees of compression of the spring, the point of support of the spring changing along the convolutions ¹⁰ of the member as the compression is varied.

In testimony whereof, I have hereunto subscribed my name this 23d day of November, 1920.

WARREN B. FLANDERS.
